DESIGN FOR A PICTURE FRAME.

JOHN H. BELLAMY, OF CHARLESTOWN, MASSACHUSETTS.

Design No. 2,523, dated December 11, 1866.

The Schedule referred to in these Letters Patent and making part of the same.

TO WHOM IT MAY CONCERN:

Be it known that I, JOHN H. BELLAMY, of Charlestown, in the county of Middlesex, and State of Massachusetts, have invented a new and improved Design for a Picture Frame; and I hereby declare that the following is a full and exact description thereof, reference being had to the accompanying photograph drawing and to the letters of reference marked thereon.

My invention consists of a picture frame, surrounded by emblematic symbols, so arranged as to produce an open-work design. In the accompanying photograph, at the top of the frame, (1,) are a tent, (1,) a bundle of rods, (2,) a horn of plenty, (3,) an open hand with a heart in the palm, (4,) a cross with a serpent entwined around it, (5,) a bidden rod, (6,) two tablets, (7,) scales with sword, (8,) an hour-glass, (9,) an eye, (10,) a bee around it, (11,) a book, (12.) On either side of the frame (A) is a pillar surmounted with a globe, (13.) At the base of the frame (A) are three pillars, (14,) three arrows, (15,) a bow with quiver and a rod, (16,) seven stars, (17,) the moon, (18,) three links, (19,) an axe, (20,) two arks, (21,) and an anchor, (22,) the whole being supported by ornamental scroll work.

What I claim as my invention, and desire to secure by Letters Patent, is—

The design for a picture frame, substantially as shown and described.

JOHN H. BELLAMY.
